UNITED STATES PATENT OFFICE

PHILIP L. HAIMS, OF CLEVELAND, OHIO

HAIRPIN

Application filed March 31, 1930. Serial No. 440,285.

This invention relates to hair pins and particularly to hair pins for use on bobbed hair.

The object of the invention is to provide a hair pin which is capable of being easily manipulated in the act of applying it to the hair, separating the branches of the pin by a simple pressure and when said pressure is released the pin will close and securely hold the strands of hair.

The above named and other features and advantages of the invention will more fully appear from the following specification reference being had to the accompanying drawings, in which:

Fig. 1 is a side view of the invention in closed position.

Fig. 2 is a top plan view.

Fig. 3 is a side view showing the open position.

Fig. 4 is a perspective view showing the manner of operating.

Referring to the drawings; one inwardly bowed branch or finger of the hairpin is indicated by the numeral 1 which is bent inward as at 2, at the open end, and is also bent outward slightly at 3 near the loop 4 which connects with other branch or portion of the hairpin, this portion consisting of a straight strip 5, two angular bent portions 6 and 7 with the lower points 8 and 9 touching the inside of the branch 1, the angular portion 7 having an additional inward bent portion shown at 10 which ends in the straight strip 11 with an upflaring end 12.

The pin is made of a strip of flat spring metal and when the fingers 13 and 14 press together the portion 3 of the finger 1 and the straight strip 5, the angular bent portion 6 acts as a fulcrum thus springing the finger 1 and the other strip 11 apart, lifting the angular bent portion 7 from the top of the finger 1, thus allowing the hair to be entered between the fingers.

A hairpin may be made with the upper portion straighter by omitting the angular bent portion 7 and adding the downward bent portion 10 to the angular bent portion 6 and extending the straight strip 11 to the

correct length which is slightly shorter than the lower or bottom portion.

There may be additional angular bent portions as indicated at 15 in Fig. 4.

It will be seen that the fingers or branches 55 of the hair pin can be spread apart by simple pressure at the rear end of the pin, which has the effect of opening the front ends, and when the pressure is released the fingers spring together to hold the hair entered therebetween. This gives a quick and easy operation and makes a secure device for fastening the hair.

I claim:

A hair pin comprising a strip of flat 65 spring metal bent to form opposite fingers and a connecting bend, one finger having a series of corrugations, the corrugation nearest the connecting bend resting in contact with the inner side of the other finger, the 70 latter finger being bowed inwardly and forming a fulcrum to open the front ends of the fingers by pressure between said corrugation and the connecting bend.

In testimony whereof, I do affix my signature.

PHILIP L. HAIMS.
